PILE APPARATUS

Alphonse Cortella, New York, N. Y., assignor to
 Cortella Laboratories Inc., New York, N. Y., a
 corporation of New York

Application June 18, 1940, Serial No. 341,079

7 Claims. (Cl. 61—73)

This invention relates generally to apparatus for driving piles. More particularly my invention relates to an improved apparatus for placing cased, cast-in-place piles.

One of the objects of my invention is to provide a pile apparatus of the class described which shall be so designed that relatively thin shells may be efficiently and practically employed to act as forms for concrete or other suitable filling in order to construct a pile, thus effecting a great saving of material.

Another object of my invention is to provide an improved pile apparatus of the class described in which a single shell or a plurality of joined shells are employed, which shall be so constructed that the shells themselves or the joints between shell sections will not be subjected to any of the driving forces of the pile apparatus resulting from the hammer blows.

Still another object of my invention is to provide an improved pile apparatus of the class described which shall be characterized by its novel constructional features, by its simplicity of assembly and operation and by its high degree of efficiency.

Further objects of my invention will become apparent in the following detailed description thereof.

In the accompanying drawing,

Fig. 1 is an elevational view of a pile apparatus constructed and arranged in accordance with my invention;

Fig. 2 is an enlarged vertical sectional view of the apparatus shown in Fig. 1;

Fig. 3 is a top plan view thereof;

Fig. 4 is an enlarged sectional view of a fragment of the apparatus shown in Fig. 2;

Fig. 5 is an elevational view similar to Fig. 1 but illustrating a modified form of my invention; and

Fig. 6 is an enlarged vertical sectional view of a fragment of the apparatus shown in Fig. 5.

Referring to the drawing, I have shown, in Figs. 1 to 4, an apparatus for forming a cast-in-place pile constructed in accordance with my invention and comprising a driving tube or pipe 10 made of rigid material such as metal, concrete, plastics or the like substances able to withstand the force of the driving blows delivered thereto by means of a steam hammer or any other similar driving means. Resting upon the upper end of the pipe 10 is a cylinder 11 having its base 11a directly contacting the rim of the said pipe 10. A downwardly depending flange 12 disposed closely adjacent the inner wall of

the pipe 10 serves to prevent relative lateral displacement between the cylinder base 11a and the said pipe 10. A suitable pin 14 passing through the walls of the flange 12 and pipe 10 serves to additionally maintain the cylinder 11 in attachment with the pipe 10. The cylinder 11 normally contains a predetermined quantity of water or any other suitable fluid. Mounted for vertical movement within the cylinder 11 and normally disposed at about the water line therein is a relatively heavy metallic plate 15 which is attached to the base 16 of a suitable steam hammer (not shown) of the type known to the art, by means of a chain or bail member 17 as shown. A packing member 18 carried by the plate 15 is interposed between the plate 15 and the inner wall of the cylinder 11 to provide a water-tight fit, the purpose of which will soon become apparent.

At the lower end of the drive pipe 10 there is provided a plate 19 which is made stronger than the drive pipe 10 because of the fact that it is this member 19 which bears the brunt of the driving force of the hammer. The plate 19 may be a separate member as shown in the drawing or it may be made integral with the pipe 10, if desired. Also while the plate 19 is shown flat in Fig. 2, the same may be tapered as in Fig. 5 or it may have any other desired shape depending upon the specific job undertaken.

Surrounding the plate 19 is a boot member 24 which may be of rigid metallic material.

Surrounding the drive pipe 10 is a sheath 20 made of rubber or any other similar elastic material which is preferably of the type adapted to readily stretch or permit expansion in a radial direction and to resist expansion in an axial direction. One manner of effecting such construction for the rubber sheath 20 is to reinforce the said sheath 20 with longitudinal wires or cords adapted to expand radially but not capable of expansion along the lengths thereof.

At a point adjacent the upper end of the pipe 10 a tightly drawn band 21 rigidly attaches the sheath 20 to the pipe 10, at the same time forming a fluid-tight joint. A similar band may be employed adjacent the lower end of the pipe 10 for the same purpose and function as that of the band 21. If desired, instead of the bands 21, a plurality of tightly drawn wires 22 may be satisfactorily used as shown in Fig. 2 of the drawing.

Surrounding the rubber sheath 20 is a tubular shell 25 which, due to special features of con-

struction of my improved apparatus, may be made of relatively thin material. The shell 25 may be transversely or otherwise corrugated, to withstand earth pressure after the driving pipe 10 and plate 15 have been removed and before the shell is filled with concrete. The bottom of the shell 25 is rigidly attached to the boot member 24 for movement therewith by any suitable attaching means, such as, for example, by welding as at 23. The upper end of the shell 25 is free and unattached. It is noted that the shell 25 is normally spaced from the sheath 20 a predetermined distance, the reason for which will soon be explained.

By means of the piping 26 water in the cylinder 11 may be caused to flow therefrom into the space between the pipe 10 and the sheath 20.

It is thus seen from the above description of the apparatus that the weight of the hammer 16 resting on the plate 15 will cause the said plate 15 to move downwardly in the cylinder 11. This in turn will force the water from the cylinder 11 to flow under pressure through the piping 26 and in between the rubber sheath 20 and the drive pipe 10 to expand the said rubber sheath 20 away from the said pipe 10 and up against the surrounding shell 25. In Fig. 2, the relative positions of the parts are shown when the water from the cylinder 11 is still being forced into the space between the pipe 10 and the sheath 20. Fig. 3 illustrates the relative positions of the parts when the plate 15 has been lowered to a point where it rests upon the base 11a of the cylinder 11, in which case all the water from the cylinder will have been forced into the space between the sheath 20 and pipe 10. The blows of the hammer 16 are then delivered through the plate 15 and the cylinder base 11a to the drive pipe 10. The blows thus delivered by the hammer 16 are transmitted to the plate 15 which pushes the earth aside as it moves downwardly. The boot 24 is also carried down by the plate 15 and the shell 25 which is attached to the boot 24 will also move downwardly.

It is thus seen that no strain of the hammer blows is imposed on the shell 25, since it is merely dragged along by the downward movement of the boot 24.

When the hole for the pile has been driven to the required depth, the weight 16 is lifted by means of the bail 17. This will cause the plate 15 to rise creating a suction within the cylinder 11 into which the water from between the sheath 20 and drive pipe 10 flows. The structure is so designed that when the plate 15 travels upwardly to a position where it abuts a member 28 all the water will have been emptied from the space between the pipe 10 and the sheath 20 into the cylinder 11. This will cause the said sheath to be restored to its original collapsed position. The cylinder 11 may then be lifted, carrying with it the drive pipe 10. It is noted that the pipe 10 may be readily removed in view of the free space surrounding the same due to the above described action of the expanding rubber sheath 20. Concrete or other suitable filling material may then be poured into the opening defined by the shell 25 to form a pile.

In Figs. 5 and 6 I have shown the application of my invention as applied to a type of pile apparatus comprising a plurality of shells A, B and C joined in step-taper arrangement. In the type of step-taper piles heretofore employed, the joints of the sections had to be made strong enough to withstand the force of the hammer blows as it was

driven into the ground. In the apparatus of my invention, however, the joints between shell sections A and B and B and C need only be made water-tight to prevent water from the surrounding earth from entering the shell 25 when the apparatus comprising the driving pipe 10 and the rubber sheath 20 is removed therefrom and until the shell is filled with concrete or the like. One such type of water-tight joint is shown in Fig. 6 of the drawing. In this form of my invention the rubber sheath 20 may be step-tapered to correspond to the taper of the shell. As no driving force is applied to the shell the joints between sections thereof will easily hold and prevent the leakage of water into the shell.

One of the advantages of the present invention lies in the fact that while the shell 25 may be under tension due to the pulling action of the boot 24, the said shell is never under compression and therefore will not buckle as would be the case in the type of pile apparatus heretofore employed. It is noted that even the tension to which the shell 25 is subjected is limited, due to the flexible rubber sheath engaging in the corrugations of the shell 25, as clearly shown in Fig. 4 of the drawing.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the most general results outlined, and the invention extends to such use.

Having described my invention, what I claim and desire to secure by Letters Patent is:

1. In a pile driving apparatus of the class described the combination of a relatively rigid driving member responsive to hammer blows, a resilient sheath of resilient material surrounding said driving member and a shell surrounding said sheath, said shell being normally spaced from said sheath, and means for causing said sheath to move radially in a direction away from said driving member and toward said shell, said last named means comprising a chamber containing a liquid and piping leading from said chamber to a space between said driving member and said sheath to permit said liquid to expand said resilient sheath.

2. In a pile driving apparatus of the class described the combination of a relatively rigid driving member responsive to hammer blows, a resilient sheath surrounding said driving member, a shell surrounding said sheath, means for causing said sheath to expand in a direction away from said driving member and toward said shell, said last named means comprising a chamber containing a liquid, piping leading from said chamber to a space between said driving member and said sheath to permit said liquid to expand said sheath, and means to force the liquid from said chamber through said piping and into said space.

3. A pile driving apparatus comprising a driving member responsive to hammer blows, a boot member at the lower end of said driving member disposed in the path of movement of said driving member, an expansible sheath surrounding said driving member, a shell normally spaced from and surrounding said sheath, said shell being at-

tached to said boot member for movement therewith whereby the said shell will be pulled downwardly with the movement of said boot member by a force exerted adjacent the bottom of said shell, means for causing said sheath to expand in a direction away from said driving member to frictionally engage said shell, said last named means comprising a cylinder containing a liquid, and means for introducing said liquid between said sheath and said driving member to expand said sheath.

4. A pile driving apparatus comprising a driving member responsive to hammer blows, a boot member at the lower end of said driving member disposed in the path of movement of said driving member, an expansible sheath surrounding said driving member, a shell normally spaced from and surrounding said sheath, said shell being attached to said boot member for movement therewith whereby the said shell will be pulled downwardly with the movement of said boot member by a force exerted adjacent the bottom of said shell, a cylinder having the bottom wall thereof contactively engaging said driving member, liquid in said cylinder, piping communicating with said cylinder to permit the flow of said liquid to a space between said sheath and said driving member.

5. A pile driving apparatus comprising a driving member responsive to hammer blows, a boot member at the lower end of said driving member disposed in the path of movement of said driving member, an expansible sheath surrounding said driving member, a shell normally spaced from and surrounding said sheath, said shell being attached to said boot member for movement therewith whereby the said shell will be pulled downwardly with the movement of said boot member by a force exerted adjacent the bottom of said shell, a cylinder having the bottom wall thereof contactively engaging said driving mem-

ber, liquid in said cylinder, piping communicating with said cylinder to permit the flow of said liquid to a space between said sheath and said driving member, and a piston member in said cylinder for forcing the liquid therefrom into said space.

6. A pile driving apparatus comprising a driving member responsive to hammer blows, a boot member at the lower end of said driving member disposed in the path of movement of said driving member, an expansible sheath surrounding said driving member, a shell normally spaced from and surrounding said sheath, said shell being attached to said boot member for movement therewith whereby the said shell will be pulled downwardly with the movement of said boot member by a force exerted adjacent the bottom of said shell, a cylinder having the bottom wall thereof contactively engaging said driving member, liquid in said cylinder, piping communicating with said cylinder to permit the flow of said liquid to a space between said sheath and said driving member, and a piston member in said cylinder for forcing the liquid therefrom into said space, said piston member being so constructed and arranged as to force all the liquid from said cylinder so that it will contactively engage the said bottom wall of said cylinder to thereafter receive the force of said hammer blows.

7. In a pile driving apparatus of the class described, the combination of a relatively rigid driving pipe or core and a sheath of elastic material, said core being nested within said sheath, means for attaching adjacent portions of the top and bottom of said sheath to said core for movement therewith, leaving the sheath portions between said top and bottom attached portions free to expand radially with respect to said core, and means for causing such expansion of said sheath.
